(57) **CLAIM**

The ornamental design for a brush, as shown and described.

DESCRIPTION

FIG. 1 is a top, front and left side perspective view of the brush of my new design;
 FIG. 2 is a left side elevational view thereof;
 FIG. 3 is a top plan view thereof;
 FIG. 4 is a right side elevational view thereof;
 FIG. 5 is a bottom plan view thereof;
 FIG. 6 is a front elevational view thereof;
 FIG. 7 is a rear elevational view thereof;
 FIG. 8 is a bottom, rear and right side perspective view thereof; and,
 FIG. 9 is an exploded view of the brush illustrated in FIG. 1.
 The broken lines in the drawings depict portions of the brush that form no part of the claimed design.
